UNITED STATES PATENT OFFICE.

KAY M. CROSSEN, OF LIMA, OHIO.

ATTACHMENT FOR LOCKS.

Application filed March 22, 1926. Serial No. 96,541.

This invention relates to attachments for locks and more particularly to a shield to protect the key of the transmission lock of a motor vehicle.

5 Certain types of transmission locks are so constructed that the key can only be removed when the lock is in operative position thus making it necessary to keep the key in the lock whenever the lock is released 10 and the vehicle is in operation.

As the lock is arranged just above the floorboard of the vehicle the projecting portion of the key is apt to be accidentally broken off. This leads to considerable annoyance and expense in removing the portion of the key from the lock.

An object of the present invention is to provide a shield which is adapted to surround the lock casing and protect the key 20 from injury.

A further object is to provide a device of this character which will not interfere with the normal operation of the transmission.

In the accompanying drawings I have 25 shown one embodiment of the invention. In this showing,

Figure 1 is a perspective view of a transmission socket showing the invention applied,

30 Figure 2 is a plan view of the shield removed,

Figure 3 is a vertical sectional view of the shield substantially on line 3-3 of Figure 2, showing the shield in position on 35 the transmission socket or base, and

Figure 4 is a similar view substantially on line 4-4 of Figure 2.

Referring to the drawings the reference numeral 1 designates a transmission socket 40 of the usual construction which is arranged to project above the floor-board (not shown) of a motor vehicle and is adapted to receive the usual transmission lever 2 which extends upwardly to a point adjacent the 45 driver's seat and the lower end of which, within the socket 1, controls the gearing.

In the usual construction of transmission locks the lock is arranged in a casing 3 beside the socket 1 and is controlled by a key 4 in the usual manner. As shown, the lock 50 casing generally terminates at a point below the top of the socket 1.

The attachment forming the subject matter of the present invention consists of a 55 shield preferably formed of sheet metal or

the like and consisting of a curved vertical wall 5 which is suitably shaped to surround the socket 1 and the lock casing 3. Adjacent the socket 1 the wall projects above the top of the socket (see Figures 3 and 4) and 60 the upper portion thereof is closed by a plate 6. This plate is provided with an opening 7 which is of greater diameter than the diameter of the transmission lever to permit free operation of the lever in shifting 65 the gearing.

Beyond the transmission socket the upper edge of the vertical wall 5 is inclined downwardly as indicated at 8 and the top of this portion of the shield is open as at 9 (see Figures 1 and 2). This inclined edge is arranged above the top of the key as clearly shown in Figure 4 of the drawings, thus forming a shield for the key and preventing it from being kicked and broken by a person getting 70 into or out of the vehicle.

Suitable means may be provided for anchoring the shield to prevent rattling due to vibration when the vehicle is in motion. As shown, the side wall 5 may be provided 80 with a thickened portion 9' having a threaded opening adapted to receive a set screw 10 which engages the side of the transmission socket as shown in Figure 3 of the drawings.

In place of the set screw 10, I may employ a spring 11 which is curved and arranged substantially parallel to the rear portion 12 of the shield. As shown, the lower end of the spring is secured to the shield as at 13 90 and the upper free end 14 is adapted to engage the adjacent portion of the lock casing.

The operation of the device will be apparent from the foregoing description. The shield is placed in position and may be anchored by the set screw 10 or the spring 11. The opening 7 is sufficiently large to permit free operation of the transmission lever 2 when changing the gear ratio. The open portion 9 of the shield permits free access 100 to the key 4 for locking and unlocking the transmission lock but at the same time the vertical wall 5 prevents the operator's foot from accidentally contacting with the key while in the lock and breaking it.

It is to be understood that the form of my invention herewith shown and described is to be taken as a preferred example of the same and that various changes in the shape, size, and arrangement of parts may be re- 110

sorted to without departing from the spirit of the invention or the scope of the subjoined claims.

I claim:

- 5 1. In a device of the character described, a shield adapted to surround a transmission socket and a transmission lock casing of a motor vehicle, said shield extending above said lock casing and being adapted to protect a key inserted therein, the top of said shield above said lock casing being open, and a spring arranged between said shield and said lock casing to normally hold said shield in position.
- 10 15 2. In a device of the character described a shield adapted to surround a transmission

socket and a transmission lock casing of a motor vehicle, said shield extending above said lock casing and being adapted to protect a key inserted therein, said shield comprising a substantially vertical wall, a top connected to said vertical wall and arranged over said socket, said top being provided with an opening for the transmission lever, the top of said shield over said lock casing being open, and a curved spring secured at one extremity interiorly of said shield and having a portion adapted to engage said lock casing for retaining said shield in position.

In testimony whereof I affix my signature.
KAY M. CROSSEN.
